UNITED STATES PATENT OFFICE.

GEORGE W. BROOKS, OF TOPEKA, KANSAS.

METALLIC FURNITURE.

1,052,794.

Specification of Letters Patent. Patented Feb. 11, 1913.

Application filed March 18, 1912. Serial No. 684,470.

To all whom it may concern:

Be it known that I, GEORGE W. BROOKS, a citizen of the United States of America, and resident of Topeka, in the county of Shawnee and State of Kansas, have invented certain new and useful Improvements in Metallic Furniture, of which the following is a specification.

This invention relates to metallic furniture, such as sectional unit filing devices, and it has for its objects among others to provide a simple and improved construction equipped with a locking device for fastening the sections or units together so that they cannot become detached by accident and by means of which different sections may be taken out or removed without danger of the other sections coming apart or disturbing their contents in any way. The device is simple in the extreme and sections may be put together or any one of them removed with ease, the sections locating themselves as they are placed together and the lock being positive in its action.

I construct the unit of a single piece of metal which is given the shape desired and provided with stiffening ribs, those at the top of the unit forming guides for the movably mounted locking bars.

Other objects and advantages of the invention will hereinafter appear and the novel features thereof will be particularly pointed out in the appended claims.

The invention is capable of embodiment in a variety of forms and the locking device is applicable to various forms of sectional furniture such as vertical letter files, or cases of any description requiring a simple and substantial locking device. It is to be understood, however, that the invention is not to be restricted to the sectional devices of the specific character herein illustrated, those shown being merely for the purpose of demonstrating the practicability of the device forming the subject matter of the present invention and as in no way attempting to set up all of the modes of use thereof.

The invention in such forms as it has been deemed advisable to show is clearly illustrated in the accompanying drawings, which, with the numerals of reference marked thereon, form a part of this specification, and in which—

Figure 1 is a side elevation showing two sections or units fastened together by my improved locking means. Fig. 2 is an en-

larged detail vertical section on the line 2—2 of Fig. 1, looking in the direction of the arrow. Fig. 3 is a section on the line 3—3 of Fig. 2 looking in the direction of the arrow. Fig. 4 is an enlarged perspective detail of one of the locking bars showing also a portion of the bar which is employed for the purpose of connecting such bar with the one upon the opposite side. Fig. 5 is a top plan view of one of the sections or units. Fig. 6 is a front elevation. Fig. 7 is a horizontal section on the line 7—7 of Fig. 6 looking in the direction of the arrow.

Like numerals of reference indicate like parts throughout the several views.

Referring to the drawings:—1 designates one of the sections or units. In forming this unit I take a single piece of sheet metal and by suitable manipulation and machinery and devices, I shape and bend it so as to form from the one sheet the two sides and the back of the section or unit. The top edges of the sides are formed with stiffening ribs 2 which form recesses or guides for a purpose which will hereinafter appear and these ribs, which are hollow, have extending inwardly therefrom the flanges 3 to which the top plate 4 is designed to be attached by rivets or other means. The upper walls of these ribs are provided each with two longitudinally disposed slots 6, one near each end, the object of which will soon be explained. The back at the upper edge is formed with a stiffening rib 7 from which extends the inwardly disposed flange 8 which receives the rivets or other suitable means 9 which are employed for securing the top plate 4 firmly in position at the back. The front edges of the sides are formed with the strengthening ribs 10 and at the back with similar stiffening ribs 11. The back at the bottom is formed with a stiffening rib 12 and the sides at the bottom are formed with stiffening ribs 13 terminating in the inwardly extending flanges 14, upon which rests the bottom plate 15 designed to be secured thereto in any suitable manner. The bottom plate is formed with the upwardly extended ribs 16, as seen in Figs. 6 and 7, which not only strengthen the same, but which serve as partitions or divison plates, for which latter purpose they may be used, if desired. The bottom ribs 13 of the sides are formed with longitudinally disposed slots 17 for coöperation with the movable locking devices which are

mounted upon the top of the next adjacent section and which locking devices project through the slots 6 of the stiffening ribs 2 at the top of the section or unit. A section 6 or unit thus constructed will be found strong, light, not liable to warp or twist and as it can be made of any size, shape or capacity, requiring only the addition of a thin top and bottom plate to complete the 10 section, it will readily be seen that the same can be set up by unskilled labor and when complete is well braced and is practically indestructible.

For locking adjacent sections or units together, I employ a locking bar 18 upon each 15 side, each bar being mounted for movement within the guiding rib 2 and the two bars connected at the front end by a transverse bar 19 secured thereto in any suitable manner, as by rivets 20', see Fig. 3. Each bar has one or more locking hooks or latches 20 projecting from its upper face and extending preferably toward the front of the unit or section. These hooks may be formed 25 in any suitable manner, for instance, they may be struck from the bar and bent up at right angles thereto, as indicated in Fig. 4, where 21 designates the space or opening left in the bar by the cutting away of the 30 material to form such hooks or latches, although it is evident that these may be formed in other ways, as, for instance, being made separate and riveted to the bar 18, which I should consider the full equivalent 35 of the form of construction shown in Fig. 4. These bars are mounted for sliding movement within the ribs 2 with the hooks 20 projecting through the openings 6 in such side stiffening ribs. These strengthening ribs 2 have the material which is struck up to form the opening 6 bent inwardly from opposite sides forming the guiding flanges 22 which engage in the guiding 40 grooves 23 formed in the opposite sides of the hook or latch 20, as seen best in Fig. 2.

24 is a screw having its inner end engaged in a threaded opening in a lug 25 projecting upward from the cross bar 19 which connects the two bars 18, this screw being 50 mounted for free rotation within an upstanding flange 26 at the front of the unit or section at the top. Manipulation of this screw controls the backward and forward movement of the bars 18, as will be readily 55 understood. This screw further serves for securing the locking bars in position as well as permitting their release.

27 are springs preferably in the form of substantially flat springs, one arranged near 60 each end of the bar 19, each spring having one end seated in a kerf or the like 28 in the bar 19 and the other end slightly bent, as at 29, and engaged in the flange 26 at the top of the front of the unit, as indicated 65 clearly in Fig. 5. These springs tend to

automatically keep the hooks in their locked position whether the screw be in its loose or tight condition.

If desired, the bars 18 may be provided at their rear ends with the lugs or flanges 70 30 to limit their forward movement, although this is not necessary.

The raised edges or guiding members 22 serve as guides or steady pins and locate the different sections in their proper position, so they can be readily latched. Upon reference to Fig. 3, it will be seen that the hooks 20 which project through the openings between these guide flanges 22, will, when the bar 18 is moved in the direction of the arrow seen in Fig. 3, engage over the adjacent face 32 of the top rib 2 of the one section and the bottom wall 31 of the bottom rib 13 of the upper section and that when thus engaged, the sections cannot move 80 relatively to each other in any direction and that they are firmly held in position. Movement of the cross bar 19, and, consequently, the side bars 18, toward the rear 85 disengages the hooks from the coöperating portions of the two sections or units, when the latter can be readily separated.

From the foregoing, it will be seen that I have devised a novel form of unit or section, as well as efficient locking means for 95 adjacent sections or units, and while the structural embodiment of the invention as hereinbefore disclosed is what I at this time consider preferable, it is evident that the same is subject to changes, variations and 100 modifications without departing from the spirit of the invention or sacrificing any of its advantages. I, therefore, do not wish to restrict myself to the precise construction, proportion of parts, etc., as hereinbefore disclosed, but reserve the right to make such changes, variations and modifications as come properly within the scope of the protection prayed.

What is claimed as new is:—

1. A pressed sheet metal sectional unit comprising a back and sides formed from one integral element, said back being formed at its upper edge with a stiffening rib with inwardly extending flange and the sides 115 formed at their front edges with vertically disposed stiffening ribs and at their rear edges with vertically disposed stiffening ribs.

2. A pressed sheet metal sectional unit 120 comprising a back and sides formed from one integral element, the sides being formed with vertically disposed stiffening ribs at the back and front edges and the back formed at its upper edge with a stiffening 125 rib with inwardly disposed flange, said sides having hollow stiffening ribs at their upper edges provided with longitudinally disposed openings.

3. A pressed sheet metal sectional unit 130

- comprising a back and sides formed from one integral element, the top edges of the sides being formed with hollow stiffening ribs provided with longitudinally disposed 5 openings in their upper walls and with inwardly extending flanges and the back at its upper edge formed with a stiffening rib with inwardly disposed flange.
4. A pressed sheet metal sectional unit 10 embodying a back and sides in one integral element, the top edges of said sides being formed with hollow stiffening ribs with inwardly extending flanges, the back being formed at its upper edge with a stiffening 15 rib with an inwardly extending flange and at the bottom with a stiffening rib, the sides being formed also at the bottom with stiffening ribs having inwardly extending flanges.
5. A sectional unit embodying a back and 20 sides in one integral element, said sides having hollow stiffening ribs at their upper ends, said ribs being provided with longitudinally disposed openings, combined with fastening means movable in said hollow ribs 25 and having members projecting through said openings.
6. A sectional unit embodying a back and sides in one integral element, said sides having hollow stiffening ribs at their upper 30 ends, said ribs being provided with longitudinally disposed openings, combined with fastening means movable in said hollow ribs and having members projecting through said 35 openings, said members being of hook form.
7. A sectional unit embodying a back and sides in one integral element, said sides having hollow stiffening ribs at their upper ends, said ribs being provided with longitudinally disposed openings, combined with fastening means movable in said hollow ribs 40 and having members projecting through said openings, said members being of hook form, said openings having oppositely disposed 45 guiding flanges.
8. A sectional unit embodying a back and sides in one integral element, said sides having hollow stiffening ribs at their upper ends, said ribs being provided with longitudinally disposed openings, combined with fastening means movable in said hollow ribs 50
- and having members projecting through said openings, said members being of hook form, said openings having oppositely disposed guiding flanges and the hook member 55 having grooves coöoperating therewith.
9. A sectional unit, the sides of which are provided at their upper ends with hollow stiffening ribs having openings and at the bottom with hollow stiffening ribs having 60 openings, combined with movably mounted bars in the top ribs and provided with hook members movable through the openings thereof for coöperation with the openings in the bottom ribs of an adjacent unit.
10. A sectional unit having hollow ribs at the sides at the top and provided with openings, bars movable in said ribs and having hook members projecting through said 65 openings, and means connecting the front ends of said bars.
11. A sectional unit having hollow ribs at the sides at the top and provided with openings, bars movable in said ribs and having hook members projecting through said openings, means connecting the front ends of said bars, and a spring acting on said connecting means.
12. A sectional unit having hollow ribs at the sides at the top and provided with 70 openings, bars movable in said ribs and having hook members projecting through said openings, means connecting the front ends of said bars, and a controlling device adjustably connected with said connecting 75 means.
13. A sectional unit having hollow ribs at the sides at the top and provided with openings, bars movable in said ribs and having hook members projecting through said 80 openings, means connecting the front ends of said bars, a controlling device adjustably connected with said connecting means, and springs upon opposite sides of said controlling device acting upon said connecting 85 means.

Signed by me at Topeka, Kansas, this 8th day of March 1912.

GEORGE W. BROOKS.
